Primary Examiner — Amy C Wierenga(74) *Attorney, Agent, or Firm* — Mark Wisnosky(57) **CLAIM**

The ornamental design for a saddle connector, as shown and described.

DESCRIPTION

FIG. 1 is a front elevation view of a saddle connector;
 FIG. 2 is a front elevation view of the saddle connector shown in use on a pipe;
 FIG. 3 is a front view thereof;
 FIG. 4 is a back view thereof;
 FIG. 5 is a right side view thereof;
 FIG. 6 is a left side view thereof;
 FIG. 7 is a top view thereof; and,
 FIG. 8 is a bottom view thereof.
 The broken lines in FIG. 2 illustrate environmental structure that form no part of the claimed design.

1 Claim, 8 Drawing Sheets(56)
